UNITED STATES PATENT OFFICE.

OTTO B. ELKINS AND MARSHAL S. SMITH, OF ABBEVILLE, GEORGIA, ASSIGNEES OF
ONE-FOURTH TO NATHANIEL STATHAM, OF ABBEVILLE, GEORGIA.

DENTAL-RUBBER-DAM HOLDER AND CUTTER.

1,230,284.

Specification of Letters Patent. Patented June 19, 1917.

Application filed July 6, 1916. Serial No. 107,828.

To all whom it may concern:

Be it known that we, OTTO B. ELKINS and MARSHAL S. SMITH, citizens of the United States, residing at Abbeville, in the county 5 of Wilcox and State of Georgia, have invented certain new and useful Improvements in Dental - Rubber - Dam Holders and Cutters; and we do declare the following to be a full, clear, and exact description of the 10 invention, such as will enable others skilled in the art to which it appertains to make and use the same.

This invention relates to improvements in devices for feeding and cutting lengths of 15 material from a continuous strip or roll.

The object of the invention is to provide a simply constructed apparatus of this character in which a spring actuated feed roller is controlled by a reciprocatory member at 20 the will of the operator.

Another object is to provide simple and efficient means for severing the material so fed in any desired lengths.

With the foregoing and other objects in view, which will appear as the description proceeds, the invention resides in the combination and arrangement of parts and in the details of construction hereinafter described and claimed, it being understood that 30 changes in the precise embodiment of the invention herein disclosed may be made within the scope of what is claimed without departing from the spirit of the invention.

In the accompanying drawings:

Fig. 1 is a front elevation partly in 35 section of this improved holder;

Fig. 2 is a bottom plan view thereof;

Fig. 3 is an end elevation;

Fig. 4 is a transverse section taken on the 40 line 4—4 of Fig. 1;

Fig. 5 is a similar view taken on the line 5—5 of Fig. 1;

Fig. 6 is a longitudinal section thereof taken on the line 6—6 of Fig. 3;

Fig. 7 is a similar view with the axle removed and looking from the rear;

Fig. 8 is a detail perspective view of one of the toothed disks employed in the formation of the feeding wheel; and

Fig. 9 is a transverse section on the line 50 9—9 of Fig. 6.

In the embodiment illustrated, a cylindrical casing 1 is shown closed at one end and provided at its other end with a removable closure in the form of a cap 20. This cyl-

inder has a slot 2 extending longitudinally throughout its length and through which the material to be fed is designed to pass.

Rising from the outer face of the upper wall of said slot is a sheath 3 for housing 60 and guiding a movable knife blade 5 which operates through a slot 4 in one end of the sheath.

This blade is held yieldably in raised position by a coiled spring 5' secured at one 65 end to said knife and at its other end to the sheath 3. A stationary knife 6 is secured to the outer face of the lower wall of the casing slot 2 and co-operates with the movable blade to form a shearing cut on the material fed 70 out through said slot.

Arranged within the casing 1 on opposite sides of the slot 2 are rotatably mounted feeding rollers 7 and 8, one of which is movable toward and away from the other 75 for clamping the strip to be fed between them. The stationary roller 8 has a cog 9 shown arranged on its outer end, which is the end positioned at the cap carrying end of the casing and which is designed for a purpose to be described.

The outer end of the roller 7 has an arm or link 10 engaged therewith and extending laterally therefrom through an aperture in the casing adjacent the slot 2. A cam lever 85 11 is engaged with the outer end of this link 10 and is operable to draw the link out through the casing and thereby move the roller 7 away from the roller 8 to permit the strip S to be fed between said rollers to be 90 inserted.

A coiled spring 12 mounted on the link 10 between the roller 7 and the casing wall exerts its tension to force the roller 7 toward the roller 8 and hold it in yielding engagement therewith. A wear plate 13 is engaged with the opposite faces of the casing around the aperture therein through which the link 10 passes. This plate extends through a slot in the casing and has a groove 14 on its 100 outer face in which the lever 11 operates. This lever 11 is shown bifurcated with the link 10 extending between the furcations thereof and pivotally connected therewith. The cam portion 15 of the lever is held in 105 yielding engagement with the wear plate 13 and said lever is provided with a finger notch 16 although obviously any suitable gripping means may be provided to facilitate its operation. It will thus be seen that 110

by swinging the lever outward the roller 7 will be moved away from the roller 8 and when said lever is released the roller will be returned by the spring 12.

5 The casing 1 is also provided with a longitudinal slot 17 through which a reciprocating member in the form of a stud 18 projects into the casing. This stud 18 which is designed for coöperation with a feed roller or ratchet wheel to be described and 10 is carried by a block 18' mounted to slide in guides 19 arranged on opposite sides of said slot.

A roll carrying shaft or axle 21 is rotatably mounted in the casing 1, the closed 15 end of said casing having a central bearing 22 to receive and support one end of the axle, the other end thereof extending through and rotating in the cap 20. This 20 axle 21 has a clutch member 23 near its outer end which coöperates with a clutch member 24 on the inner end of a sleeve 25 rotatably mounted on said axle beyond its clutch member 23, said axle being reduced 25 beyond its clutch member 23 to receive said sleeve so that when the parts are assembled, the sleeve will be of the same diameter as the body portion of the axle.

This sleeve clutch member 24 is held in 30 locking engagement with the axle clutch member 23 by means of a coiled spring 26 arranged on the outer end of the axle between a laterally extending flange 27 on the outer end of said sleeve and a nut 28 which 35 is screwed on said axle end and by means of which the tension of the spring may be regulated.

A sleeve operating finger 29 projects laterally therefrom and is designed for rotating 40 the sleeve to wind up a coiled spring 30 arranged in the cap 20. This spring 30 is secured at one end to said sleeve 25 and at its other end to the cap 20, and exerts its tension to rotate the axle in a direction 45 opposite to the direction the sleeve is turned for feeding or unwinding the material from the roll carried by the axle. The interlocking faces of the clutch members 23 and 24 are in the form of ratchet teeth to provide 50 for the turning of the sleeve 25 in one direction and to lock it against turning in the opposite direction so that the unwinding of the spring 30 will operate to rotate the axle, while the winding up thereof will 55 not affect any movement of the axle, which is owing to the fact that the sleeve is turned independently of the axle for winding up the spring.

A gear wheel 31 is fixed to the axle 21 in 60 position to mesh with the cog on the roller 8 so that the rotation of the axle will operate also to turn the rollers 7 and 8. Longitudinally spaced annular disks 32 and 33 are fixed to the axle 21 and between which is 65 disposed the roll of material to be carried by

the casing and fed therefrom, said material being preferably a strip of rubber such as is used for rubber dams by dentists.

The inner disk 33 is provided on its outer face with teeth 34 which coöperate with 70 similar teeth 35 on the opposed face of a wheel or disk 36 fixed to the shaft adjacent the disk 33 to form what may be termed a measuring or feeding wheel with which the reciprocating stud 18 coöperates to lock and 75 release the axle and permit it to rotate step-by-step under the tension of the spring 30, whereby the strip S is intermittently fed through the slot 2 in the casing, the rollers 7 and 8 coöperating therewith to feed and 80 guide the strip in its passage from the casing. The teeth on the disk 33 alternate with those on disk 36 to permit the stud 18 to move between the teeth of the two members and engage first one and then the other 85 on the reciprocation of the block 18 carrying the stud.

The disks 32 and 33 and the disk 36 have registering notches 37 to provide for the removal of the axle from the casing without 90 interference by the stud 18.

In the use of this device, the cap 20 is first removed together with the axle mounted therein and the strip S in the form of a roll is arranged on said axle between the 95 disks 32 and 33. The axle carrying the roll is then returned to the cylinder, care being taken that the notches in the disks 32 and 33 and disk 36 be aligned with the stud 18 which will permit the axle to slide freely into the 100 casing. The cap 20 is then replaced and the device is ready for use. The free end of the strip S is passed out of the slot 2 between the rollers 7 and 8 by first moving roller 7 away from roller 8 by means of 105 the lever 11, as above described. After the end of the strip S has been fed out between the rollers 7 and 8, any desired length thereof may be unrolled and fed out by reciprocating the stud carrying block 18' which 110 causes the stud 18 to engage first one tooth and then the other on the disk 33 and disk 36 respectively, thereby alternately releasing and locking the axle which turns forwardly under the action of the spring 30 and thereby unwinds the strip S while the rollers 7 and 8 feed it out of the casing. After the desired length has been fed out, it may be severed by lowering knife 25 against the tension of its spring 5'. When this knife is 120 released it is raised to normal inoperative position by the spring 5'.

I claim:

1. In a device of the class described, a casing, a roll supporting axle rotatably mounted in said casing, a spring connected to rotate said axle in one direction, and means reciprocable longitudinally relatively to said axle for locking said axle against rotation when said reciprocable means are 125 130

5 moved in one direction and for releasing the axle when said means are moved in the opposite direction, whereby a step by step rotary movement may be imparted to said axle.

2. In a device of the class described, a casing, a roll supporting axle rotatably mounted in said casing, a spring connected to turn said axle in one direction, coöperating means carried by said axle and casing for normally holding said axle against turning by said spring, one of said means being reciprocable longitudinally relatively to said axle for imparting a step by step movement 15 to said axle.

3. In a device of the class described a supporting structure, a spring actuated roll-carrying axle mounted to rotate therein, means for locking said axle from turning 20 against the tension of its spring, and means reciprocatory in a plane parallel with the axis of said axle for intermittently releasing said locking means whereby a step-by-step rotation is imparted to said axle.

25 4. In a device of the class described, a supporting structure, a spring actuated roll-carrying axle mounted to rotate therein, means for locking said axle from turning against the tension of its spring, including 30 a ratchet wheel fixed to said axle, and a stud carried by said supporting structure and movable to engage alternate teeth of said wheel whereby an intermittent rotary movement is imparted to said axle.

35 5. In a device of the class described, a supporting structure, a roll carrying axle mounted to rotate therein, a spring connected to turn said axle in one direction, a ratchet wheel fixed to said axle and having 40 alternating teeth arranged out of peripheral alinement with each other, a pin normally engaging said ratchet wheel for holding said axle against turning by said spring, said pin being reciprocable longitudinally 45 relatively to said axle for intermittently releasing said ratchet wheel for imparting a step by step movement to said axle.

6. In a device of the class described, a supporting structure, a roll-carrying axle 50 mounted to rotate therein, a spring connect-

ed to turn said axle in one direction, a reciprocatory stud mounted in said structure, a wheel fixed to said axle and having alternating laterally spaced teeth arranged in the path of said stud whereby an intermittent 55 rotary movement is imparted to said axle by said spring on the movement of said stud in opposite directions.

7. In a device of the class described, a supporting structure, an axle mounted to 60 rotate therein and having a clutch member spaced from one end thereof, a sleeve mounted to rotate on said axle beyond said clutch member and having a clutch member for coöperation with said axle clutch member 65 to lock said sleeve and axle against independent turning in one direction and permit them to turn independently in the other direction, a coiled spring secured at one end to said sleeve and at its other end to said 70 support, means for turning said sleeve to wind up said spring, means for holding said spring against unwinding, and means under the control of the operator for releasing said holding means.

75 8. A device of the class described including a casing, an axle mounted to rotate therein, a spiral spring connected to impart rotary motion in one direction to said axle, and clutch mechanism between said spring 80 and axle to provide for the winding of the spring without rotating the axle.

9. A device of the class described including a casing having a longitudinal slot 85 therein, feed rollers mounted to rotate in said casing, one of said rollers being movable laterally toward and away from the other, a lever connected to move said movable roller away from the other roller, and means for yieldingly urging said movable 90 roller toward the other.

In testimony whereof we have hereunto set our hands in the presence of two subscribing witnesses.
